[21] Appl. No.: 655,686

[57] CLAIM

The ornamental design for a golf tee sharpener, as shown.

[22] Filed: Feb. 6, 1976

DESCRIPTION

FIG. 1 is a perspective view looking downwardly toward the top and front of the golf tee sharpener of the invention.

FIG. 2 is a view in rear elevation of the golf tee sharpener.

FIG. 3 is a top plan view thereof; and

FIG. 4 is a view in side elevation of FIG. 2.
